UNITED STATES PATENT OFFICE.

ARTHUR J. WIDMER, OF WEBSTER GROVES, MISSOURI, ASSIGNOR TO WIDMER ENGINEERING COMPANY, OF ST. LOUIS, MISSOURI, A CORPORATION OF MISSOURI.

FIREPROOF FLOOR CONSTRUCTION.

1,291,326.

Specification of Letters Patent. Patented Jan. 14, 1919.

Application filed September 28, 1917. Serial No. 198,641.

To all whom it may concern:

Be it known that I, ARTHUR J. WIDMER, a citizen of the United States, and a resident of Webster Groves, in the county of St. Louis and State of Missouri, have invented a new and useful Improvement in Fireproof Floor Constructions, of which the following is a specification.

This invention relates to fire-proof floor constructions and has for its objects to eliminate unnecessary dead weight and to provide more economically than has hitherto been practised for the compressive stresses in concrete floors adjacent to their supports.

Existing types of floor construction provide additional concrete for the compressive stress at the middle of the floor spans, but more recent practice in the design of reinforced concrete floors continuous over intermediate supports requires provision in the bottom of the floor at these supports for the compressive stresses due to the negative moment.

The object of my invention is to provide additional concrete for compressive stresses in the bottom of the floor at the supports and in the upper region of the floor near the middle of the spans. My invention consists principally in making the concrete of T-shape in the middle of the spans and of inverted T-shape adjacent to the supports. The spaces between the concrete members may be filled with tiles of inverted T-shape in the middle of the spans and with tiles of T-shape adjacent to the supports.

Further details of the invention appear in the following description thereof, reference being had to the accompanying drawings, which show the invention in several forms.

In the drawings, wherein the same reference characters designate the same or similar parts in the several views,

Figure 1 is a top plan view of a concrete and tile floor embodying my invention, a portion of the concrete being broken away;

Fig. 2 is a vertical section through the floor and girder on the line 2-2 in Fig. 1;

Fig. 3 is a vertical section through the floor on the line 3-3 of Fig. 1, the left half being taken through the middle portion of the floor and the right half being taken adjacent to a girder;

Fig. 4 is a section similar to Fig. 3, showing a modified form of tile;

Fig. 5 is a fragmentary plan view of a

floor having floor tiles for a short distance on each side of the girders;

Fig. 6 is a vertical section at the middle of the floor taken parallel to the girders on the line 6-6 in Fig. 5;

Fig. 7 is a similar section taken near a girder on the line 7-7 in Fig. 5;

Fig. 8 is a vertical section through a girder, showing a portion of the floor on each side, on the line 8-8 in Fig. 5;

Fig. 9 is a fragmentary top plan view of a modified form of ribbed concrete floor;

Fig. 10 is a vertical section through the middle portion of the floor on the line 10-10 in Fig. 9;

Fig. 11 is a vertical section taken across the ribs, adjacent to a girder, on the line 11-11 in Fig. 9;

Fig. 12 is a vertical section through the floor and one of the girders on the line 12-12 in Fig. 9;

Fig. 13 is a section similar to Fig. 11, showing a modified form of covering for the spaces between the ribs adjacent to the girders;

Fig. 14 is a perspective view of one of the tiles illustrated in Figs. 1 to 4; and

Figs. 15 and 16 are perspective views of two forms of spacing members.

In the drawings, my invention is shown as applied to a floor which is continuous over intermediate supports or girders 1. The girders are supported by columns 2. In the construction shown in Figs. 1 to 3, the floor comprises parallel concrete members A alternating with tile members B. The portions 3 of the concrete members in the middle of the spans are substantially T-shaped in cross-section; the portions 4 adjacent to the supports are of inverted T-shape. The portions of inverted T-shape should extend from the supports approximately to the point of contraflexure. The spaces between the concrete members are filled with tiles 5. These tiles have ribs 6 on one surface. The ribs 6 space the horizontal portions of the concrete members apart. When the floor is laid, the tiles adjacent to the support are placed with the rib 6 underneath. The arm of the T is thus formed beneath the tiles. Reinforcing rods 7 are arranged in the concrete in the regions of tensile stress.

Fig. 4 shows a modified form of construction embodying my invention. In this modification, tiles or fillers of rectangular cross-

section are used instead of the ribbed tiles. When the floor is laid, the tiles adjacent to the supports are spaced away from the bottom of the form by spacers 8. Figs. 15 and 16 show two forms of these spacers. The concrete flows under the spacers 8, embedding them in the ceiling and making a flat surface. In the middle of the spans the tiles 5 are flush with the bottom of the floor, the arms of the concrete members being joined.

10 In the construction shown in Figs. 5 to 8, there are no tiles in the middle of the span. Adjacent to the supports, there are floor tiles 9, flush with the top of the floor. This arrangement provides a flat floor surface.

15 The construction shown in Figs. 9 to 13 has no tiles. Nailing strips 10 are arranged across the floor. The spaces between them (except adjacent to the girders) are filled with cinders 11 or other packing material. Flooring 12 is nailed to the strips 10. In Fig. 13, the channels 13 between the concrete ribs adjacent to the girders are shown as covered by plates 14, which are notched at the sides so as to be held securely in the channels.

20 Obviously, different forms of tiles or fillers may be used and other variations may be made without departing from the invention.

25 What I claim is:

30 1. A floor construction comprising supports, and parallel members of reinforced concrete continuous over the intermediate supports, said members being of T-shape in the middle regions of the spans and of inverted T-shape in the region adjacent to the intermediate supports.

35 2. A floor construction comprising supports, concrete members continuous over the intermediate supports, and tiles filling the spaces between said concrete members, said concrete members comprising T-shaped portions in the middle region of the spans and portions of inverted T-shape adjacent to the intermediate supports, all of said tiles being alike and of the same cross-section as the spaces between the concrete members.

40 3. A floor construction comprising supports, a concrete slab continuous over the intermediate supports, the middle portion of said slab comprising a horizontal top por-

tion with downwardly extending ribs, and the portions of said slab adjacent to the intermediate supports comprising a horizontal bottom portion with upwardly extending ribs.

45 4. A floor construction comprising supports, parallel members of reinforced concrete continuous over the intermediate supports, the middle portions of said members comprising an extensive upper portion with downwardly extending ribs, and the portions of said members adjacent to the intermediate supports comprising an extensive lower portion with upwardly extending ribs.

50 5. A floor construction comprising supports and parallel members of reinforced concrete continuous over the intermediate supports, the portions of said members in the middle region of the span having their main cross-sectional area in the upper region, and the portion of said members in the end regions of the span having their main cross-sectional area in the lower region.

55 6. A floor construction comprising supports, reinforced concrete members continuous over the intermediate supports, tiles filling the spaces between said concrete members, the concrete members being of T-shape in the middle region of the spans and of inverted T-shape adjacent to the intermediate supports, all of said tiles being alike and comprising an oblong body portion having a medial longitudinal rib, the outer face of said rib and the face of the opposite side of the tile being flush with the top and bottom of the concrete.

60 7. A floor construction comprising supports, parallel members of reinforced concrete continuous over the intermediate supports, the middle portions of said members comprising an extensive upper portion with downwardly extending ribs, and the portions of said members adjacent to the intermediate supports comprising an extensive lower portion with upwardly extending ribs and hollow tiles flush with the upper and lower surfaces of said members and filling the spaces between them.

65 Signed at St. Louis, Missouri, this 19th day of September, 1917.

ARTHUR J. WIDMER.
